UNITED STATES PATENT OFFICE

EARNEST D. SHEPARD, OF DALLAS CENTER, IOWA, ASSIGNOR TO EARNEST D. SHEPARD, M. M. SILKEBAKEN, AND CARRIE O. SILKEBAKEN, TRUSTEES OF UNIVERSAL UTILITY COMPANY, OF DALLAS CENTER, IOWA, A COMMON-LAW TRUST

CONTAINER SUPPORTING AND TILTING STAND

Application filed October 10, 1928. Serial No. 311,658.

The principal object of this invention is to provide a stand for supporting and holding a container such as a bottle or the like that permits and facilitates the tilting of the 5 container for pouring liquid or granular material therefrom.

A further object of my invention is to provide a stand for supporting and tilting a container such as a bottle that yieldingly holds 10 the container in a normal upright position when the container is not being manually moved and held in a pouring position.

A still further object of this invention is to provide a container supporting and tilting stand 15 that permits the easy and ready removal and replacement of the container in the same.

A still further object is to provide a container supporting and tilting stand that will 20 accommodate various sizes of containers.

A still further object of my invention is to provide a container supporting and tilting stand that not only successfully holds the container when the same is in normal upright 25 position, but prevents the container from becoming accidentally detached when the same is tilted to an extreme angle.

A still further object is to provide a stand for holding and tilting a container that is 30 economical in manufacture, durable in use, and refined in appearance.

These and other objects will be apparent to those skilled in the art.

My invention consists in the construction, 35 arrangement and combination of the various parts of the device, whereby the objects contemplated are attained as hereinafter more fully set forth pointed out in my claim and illustrated in the accompanying drawings, in 40 which:

Fig. 1 is a side elevation of my complete invention showing the container in dotted lines and illustrating its location when it is in normal upright position.

Fig. 2 is a rear end view of the device for

more fully illustrating its construction and shows the supporting legs extending downwardly and outwardly to lend rigidity to the same.

Fig. 3 is a side view of the invention illustrating the position of the container when the same is tilted for pouring out its contents. 50

Fig. 4 is a view of the stand portion of my invention showing the way in which it may be stamped from a single sheet of metal or the 55 like.

Fig. 5 is a view of the container embracing and tilting portion of the device before being bent into proper form and illustrates how it may be stamped from a single sheet 60 of metal or like.

Fig. 6 is a rear end view of a modified form of my invention in that the supporting legs are vertical and not downwardly and outwardly. 65

The obtaining of any part or all of the contents from a large container or bottle by manually lifting and tilting the same is very tiresome and difficult. Even with small containers it is almost impossible to pour out a 70 certain amount of its contents with accuracy and precision. I have overcome these disadvantages as will be appreciated by those familiar with the art. 75

As before noted the supporting stand portion of my device is stamped from a sheet of metal, thereby providing two pairs of legs which I have separately designated by the numerals 10, 11, 12, and 13 respectively. Each pair of these legs are integrally joined 80 at their top ends and extend downwardly and away from each other in the form of an inverted V. Integrally secured at one end to the leg 10 and its other end integrally secured to the leg 11 is the brace member 14, while 85 integrally secured at one end to the leg 12 and its other end integrally secured to the leg 13 is a duplicate brace member 15. Holding the two pairs of legs apart by having one end integrally formed on the leg 90

11 and its other end integrally formed on the leg 12 is the horizontal connecting brace member 16. Having one end integrally formed on the connecting brace 16, at a point near its center and extending laterally therefrom is the cross brace member 17. Integrally formed on the free end of the cross brace is the horizontal connecting brace member 18 which is an exact duplicate of the connecting brace member 16. After the blank as shown in Fig. 4 is properly bent so that the legs 10, 11, 12, and 13, will be in a proper upright position and the cross brace member 17 is bent to a horizontal position, it will be found that the two ends of the connecting brace member 18 will be adjacent the two legs 10 and 13, respectively and should be securely joined thereto by spot welding or the like.

Secured by suitable means to the cross brace 17 and extending longitudinally thereto is the leaf spring 19 as shown in the drawings. Stamped in the vertex of each of the inverted V's formed by the two pairs of legs are the holes 20.

The container embracing and tilting portion of the device is also stamped from one sheet of metal and comprises the base portion 21, which when properly bent engages the bottom of the container parallel with and adjacent the leaf spring 19, from which location it extends up along the forward side of the container until it merges into the container retaining finger 22 designed to engage the upper portion of the container and prevent the same from becoming detached from the device when the same is tilted to an extreme angle for pouring out the contents of the container. Integrally formed on the base member or portion 21 and extending in both directions therefrom are the two container embracing arms 23 and 24 designed to be bent horizontally around the container. Integrally formed on the free ends of the arms 23 and 24 and joining the same together as shown in the drawings are the two side engaging arms 25 and 26, respectively. The lower ends of these side engaging arms are bent around and under the container and secured by suitable means to the base portion 21, thereby providing a cradle for the container. Integrally formed on each of the side arms 25 and 26 are the two horizontal embracing arms 27 and 28 respectively designed to be bent around the container and then outwardly away from the container near their ends. Integrally formed on and joining each pair of these horizontal arms at their free ends are the two handle members 29 and 30 respectively. The length of these horizontal arms should be such that the two handle members 29 and 30 will be a short distance apart.

Secured by suitable means to the side arms 25 and 26 are the two rivets 31 and 32 re-

spectively, which are rotatably mounted in the holes 20 thereby supporting the container supporting and tilting portion on the stand portion and allowing the same to be rotated relative to the stand portion. Secured to the horizontal embracing arms 28 are the two stop members 33 and 34 designed to engage the two legs 11 and 12 respectively when the container supporting and tilting portion is moved to an upright vertical position thereby limiting the movement of the same to one direction. Their function is to prevent the container supporting and tilting portion to be moved past the vertical position when returning it to a normal upright position after tilting the container. The position of the rivets 31 and 32 should be so placed on the side arms 25 and 26 that when the container is in a normal upright position the leaf spring 19 will engage the base portion 21, thereby yieldingly holding the container in a normal upright vertical position.

When it is desired to pour the contents or any part of it from the container, the handle members 29 and 30 are grasped by the operator and as the container is rotatably supported at points near its center of gravity it will be easily tilted. By the grasping of the two handle members a clamping action on the container will be realized due to the fact that the tendency will be to pull them together, thereby more firmly holding the container in the device. It will be found that the contents may be poured with little exertion and with precision.

To remove the container completely from the device it is merely necessary to spread the embracing arms 27 and 28 apart so that the container may be lifted out of the device. As these embracing arms 27 and 28 are bent around the container they are easily bent to conform to containers of more than one size.

In Figure 6 the construction shown is like the construction shown in the other figures, except that the legs extend in a vertical plane instead of downwardly and outwardly. The arrangement shown in Fig. 6 is recommended when it is desired to conserve on space for the device.

In all of the drawings I have used the numeral 35 to designate the container.

Some changes may be made in the construction and arrangement of my improved container supporting and tilting stand without departing from the real spirit and purpose of my invention and it is my intention to cover by my claim any modified forms of structure or use of mechanical equivalents which may be reasonably included within their scope.

I claim:

In a container supporting and tilting stand, a stand member, a container supporting and holding member rotatably mounted on said stand member comprising, a cradle

portion designed to engage the bottom and forward side of the container to be held, arms extending from the forward portion of said cradle portion to the rear and at each side of 5 the container to be held, and a handle member secured to each of said arms; said arms terminating a slight distance apart in order that when said handle members are manually gripped to tilt said container said arms will 10 be tightened around said container for rigidly holding said container in said cradle portion.

E. D. SHEPARD.
